MATERIAL HANDLING APPARATUS

Herbert O. Bissell, Hamilton, Ohio, assignor to
Armco Steel Corporation, Middletown, Ohio, a
corporation of Ohio

Application January 13, 1950, Serial No. 138,478

9 Claims. (Cl. 202—230)

1

This invention relates to material handling apparatus and more particularly to apparatus for handling coke in a by-product coke plant.

In a coke plant it is conventional to have a battery of coke ovens disposed in a row with a track running along the discharge side of the battery of ovens for a quenching car. As the coking operation of one particular oven is finished the coke is discharged therefrom into a quenching car which is then run to a quenching tower where it is deluged with a great quantity of water in a very short time so as to lower the temperature of the coke below the combustion temperature. The quenching car then is moved to a so-called wharf which usually comprises an inclined surface lined with fire brick or the like and terminating in a series of doors or gates behind and under which passes a conveyor belt. The coke is dumped onto such a wharf and is there inspected by the wharf operator to determine whether or not any fires are present. The wharf gate walkway is equipped with water hoses and the operator manually controls these hose lines and water valves to extinguish sporadic fires which may occur. When the operator is convinced that no fires are present he opens the doors or gates mentioned above and permits the coke to pass onto the conveyor belt at a manually controlled rate, and the coke is then moved by the conveyor belt to a screening and loading station for further use. As a general practice the spot quenching operation is combined with the manual opening and closing of gates to regulate the feed of coke onto the conveyor in such a manner as to get required screening in following apparatus. Visual perception is limited by atmosphere conditions such as high or adverse winds. Physical agility on the part of the operator is important. It is, of course, of great importance to see to it that no fires are present in the coke not only because such fires are wasteful in that the coke is consumed but also because of damage to and consequent foreshortened useful service life of the conveyor belt.

It is of further importance to regulate the rate of flow of coke onto the conveyor to eliminate excessive wear thereof and spillage of coke to surrounding areas. Mechanical restraints to spillage such as skirting or baffles can be eliminated with proper regulation of feed. The alignment of the conveyor can be improved by using a single loading point which this invention provides, and thus further increase in service life can be expected.

Conditions at a coke wharf are extremely unpleasant, not only because of the heat present

2

but because of the steam, smoke and fumes issuing from the pile of coke which often render the visibility zero.

With the foregoing considerations in mind it is an object of my invention to provide means whereby the coke dumped from the quenching car is automatically inspected for fire and is automatically extinguished if fire is present and whereby the coke is fed evenly and at a predetermined rate onto the conveyor belt. It is another object of my invention to enable these operations to be carried out without the necessity of having personnel present, thereby reducing physical hazard to personnel and eliminating unpleasant working conditions.

These and other objects of my invention which I shall explain in more detail hereinafter or which will suggest themselves to those skilled in the art upon reading these specifications I accomplish by 20 that certain construction and arrangement of parts of which I shall now describe an exemplary embodiment.

Reference is made to the drawings forming a part hereof and in which:

25 Figure 1 is a plan view of an apparatus according to my invention.

Figure 2 is a front elevational view of the same.

Figure 3 is a cross sectional view taken on the line 3—3 of Figure 1, and

Figure 4 is a diagram showing the operation of the fire extinguishing means.

Briefly, in the practice of my invention I substitute for the conventional wharf, which is disposed between the quenching car tracks and the conveyor belt, a hopper which is arranged to deliver the coke through a relatively long and narrow delivery opening onto a vibratory trough which extends beyond one end of the hopper. The vibratory trough feeds the coke gradually and evenly at a predetermined rate onto the conveyor. I provide means directed at the exposed end of the trough for measuring the temperature of the coke thereon, and I also provide fire extinguishing means directed at the exposed end 45 of the trough which fire extinguishing means are made operative in response to indications from the temperature measuring means.

Referring now more in detail to the drawings, I have indicated the quenching car track at 10 and the quenching car itself is indicated at 11 and will be understood to travel on the track 10 along the front of a battery of coke ovens which will be understood to be to the left of Figure 3 and to the top of Figure 1. The quenching car 11 itself forms no part of the present invention

and may be of conventional construction and design. It usually comprises a sloping floor 12 and a door 13 by means of which the coke in the quenching car can be dumped onto the wharf.

The conveyor on which the coke is carried from the wharf is indicated at 14 and it is in all respects conventional. The return flight thereof is indicated at 15. A platform including a catwalk for inspection of the wharf is shown at 16.

Between the quenching car tracks 10 and the conveyor 14 I provide a hopper indicated generally at 17. This hopper is preferably of rectangular horizontal cross section as shown in Figure 1 and has the sloping sides 18 and 19 which converge at the bottom to a relatively narrow and relatively long delivery opening 20. Along the side of the hopper 17 adjacent the quenching car tracks I may provide a chute member 21 which will extend slightly underneath the floor of the quenching car to insure that coke being dumped from the quenching car will enter the hopper. The hopper itself may be lined with fire brick or other suitable material as indicated at 22.

Immediately beneath the delivery opening 20 I provide a trough 23 which will preferably have side and back edges as indicated at 24 and 25 respectively. The end of the trough which is on the side of the conveyor 14 extends beyond the hopper as best seen in Figure 3 and is open at the end.

In order to move the coke from the hopper along the trough to the conveyor 14 I use what is known in the trade as a vibratory conveyor feeder. Such feeders are well known and a very brief description thereof will be sufficient. The trough 20 is mounted on a series of leaf spring members 26 which in turn are mounted by means of brackets 27 or the like to a structural framework 28. The vibratory device is indicated generally at 29 and may be of the type wherein fluid under pressure enters a chamber having a diaphragm at one end to which is secured a stem for a valve disposed at the other end so that as the pressure increases the valve is opened whereupon the pressure drops, and the valve in effect vibrates back and forth rapidly. The vibration may, of course, be produced electrically or in other ways. An arm 30 secured to the vibratory member is connected to the trough 20 as indicated at 31. When the feeder 29 is operated the trough 20 is vibrated back and forth rapidly and by virtue of the sloping spring mounting at 26 the materials on the trough are caused to move toward the right in Figure 3.

The exposed end of the trough 20 which is just above the conveyor 14 is utilized for fire inspection according to the present invention. I have indicated at 32 a device known as a reflecting pyrometer. As best seen in Figure 4, this device employs a mirror 33 which focuses the heat rays entering the tube 34 to a point 35. At this point there is mounted a sensitive thermocouple indicated at 36 which is connected to amplifying means 37. Thus the current generated in the thermo-couple 36 by the heat rays focused at 35 by the mirror 33 are amplified at 37 to useful values. According to my invention the current from the amplifier 37 is used to operate a relay 38 which energizes solenoids 39 to actuate valves 40. The valves 40 control the flow of water to the quenching nozzles 41 which are directed at the exposed part of the trough 20. The reflecting pyrometers 32 are adjusted so that if any of the coke on the exposed part of the trough 20 reaches undesirably high temperature the

relay 38 will be energized to throw the solenoids 39 to open the valves 40 whereupon a spray of water is directed at the exposed part of the trough 20. One or more of the spray nozzles may also be directed at the conveyor belt itself to insure that no combustion takes place upon the belt as seen in Figure 3.

The operation of the apparatus will be evident from what has been said above. After the coke in the quenching car 11 has been quenched, the car is positioned opposite the hopper 17, and the door 13 is opened to dump the load of hot coke into the hopper 17. By means of the vibratory feeder 29 the coke is continually fed from the bottom of the hopper along a trough 20 where it is permitted to fall upon the conveyor 14. During this procedure it is subject to constant inspection by the reflecting pyrometer or pyrometers 32 so that if at any time the temperature of the coke reaches a level to endanger the conveyor, the valves are operated automatically to cause a quenching stream of water to fall at least upon the extending part of the trough and if desired also upon the conveyor 14 if it is exposed to elevated temperature.

In this way the presence of an operator is no longer required to regulate the proper flow of coke and to carry out spot quenching thereof. The hazard to personnel and the unpleasant working conditions for personnel are thereby eliminated. Weather conditions such as high or adverse winds will not hamper the uniform flow of coke to the screening apparatus which follows this operation.

35 It will be understood that numerous modifications may be made without departing from the spirit of my invention. I therefore do not intend to limit myself in any way other than as set forth in the claims which follow.

36 Having now fully described my invention, what I claim as new and desire to secure by Letters Patent is:

1. In material handling apparatus, in combination, a material hopper, a conveyor, a feeder over which said material passes from said hopper to said conveyor, a portion of said feeder being exposed, fire extinguishing means directed at the exposed portion of said feeder, and means responsive to combustion heat of said material for initiating the operation of said extinguishing means.

2. In apparatus for handling coke, in combination, a coke hopper, a coke conveyor, a feeder for feeding said coke from said hopper onto said conveyor, a portion of said feeder being exposed, fire extinguishing means directed at the exposed portion of said feeder, and means responsive to combustion heat of said coke on said exposed portion of said feeder for initiating the operation of said extinguisher means.

3. Material handling apparatus comprising a hopper for receiving material to be handled, said hopper having a delivery opening, a material receiving trough disposed below said delivery opening and extending beyond said hopper, means for producing a feed of said material toward the extending end of said trough, a conveyor disposed beneath the extending end of said trough to receive material therefrom, means for measuring the temperature of said material on the extending portion of said trough, and fire extinguishing means disposed to project a fire extinguishing substance onto said material on the extending portion of said trough, and operatively connected to said temperature measuring means to

operate in response to indications from said temperature measuring means.

4. Material handling apparatus comprising a hopper for receiving material to be handled, said hopper having a relatively long and narrow delivery opening, a material receiving trough disposed below said delivery opening and extending beyond said hopper, means for producing a regulated feed of said material toward the extending end of said trough, a conveyor disposed beneath the extending end of said trough to receive material therefrom, means for measuring the temperature of said material on the extending portion of said trough, and fire extinguishing means directed to project a fire extinguishing substance at the extending portion of said trough, said extinguishing means being operatively connected to said temperature measuring means to operate in response to indications from said temperature measuring means.

5. Material handling apparatus comprising a hopper for receiving material to be handled, said hopper being of rectangular horizontal cross section and having opposed sloping sides converging at the bottom to a relatively long and narrow delivery opening, a material receiving trough disposed below said delivery opening and extending beyond said hopper, means for producing a regulated feed of said material toward the extending end of said trough, a conveyor disposed beneath the extending end of said trough to receive material therefrom, means for measuring the temperature of said material on the extending portion of said trough, and fire extinguishing means directed to project a fire extinguishing substance at the extending portion of said trough, said extinguishing means being operatively connected to said temperature measuring means to operate in response to indications from said temperature measuring means.

6. Material handling apparatus comprising a hopper for receiving material to be handled, said hopper being of rectangular horizontal cross section and having opposed sloping sides converging at the bottom to a relatively long and narrow delivery opening, a material receiving trough disposed below said delivery opening and extending beyond said hopper, means for producing a regulated feed of said material toward the extending end of said trough, a conveyor disposed beneath the extending end of said trough to receive material therefrom, a reflecting pyrometer disposed to measure the heat of said material on the extending part of said trough, fire extinguishing means directed at the extending end of said trough, signal transmission means between said pyrometer and fire extinguishing means, and means responsive to a signal from said pyrometer that the temperature of the material on the extending portion of said trough is at combustion level for initiating the operation of said extinguishing means.

7. Material handling apparatus comprising a hopper for receiving material to be handled, said hopper having a delivery opening, a material receiving trough disposed below said delivery opening and extending beyond said hopper, means for producing a regulated feed of said material to-

ward the extending end of said trough, a conveyor disposed beneath the extending end of said trough to receive material therefrom, a reflecting pyrometer disposed to measure the heat of said material on the extending part of said trough, fire extinguishing means directed at the extending end of said trough, signal transmission means between said pyrometer and fire extinguishing means, and means responsive to an indication from said pyrometer that the temperature of the material on the extending part of said trough is at combustion level for initiating the operation of said extinguishing means.

8. Material handling apparatus comprising a hopper for receiving material to be handled, said hopper being of rectangular horizontal cross section and having opposed sloping sides converging at the bottom to a relatively long and narrow delivery opening, a material receiving trough disposed below said delivery opening, said trough being longer than said delivery opening and disposed to project beyond said hopper at one end, vibratory means for said trough to produce a regulated feed of material thereon toward the extending end thereof, a conveyor disposed beneath the extending end of said trough to receive material therefrom, means for measuring the temperature of said material on the extending end of said trough, and fire extinguishing means directed to project a fire extinguishing substance upon the extending end of said trough, said extinguishing means being operatively connected to said temperature measuring means to operate in response to indications from said temperature measuring means.

9. Material handling apparatus comprising a hopper for receiving material to be handled, said hopper being of rectangular horizontal cross section and having opposed sloping sides converging at the bottom to a relatively long and narrow delivery opening, a material receiving trough disposed below said delivery opening, said trough being longer than said delivery opening and disposed to project beyond said hopper at one end, vibratory means for said trough to produce a regulated feed of material thereon toward the extending end of said trough to receive said material therefrom, a reflecting pyrometer disposed to measure the heat of said material on the extending part of said trough, fire extinguishing means directed at the extending part of said trough, signal transmission means between said pyrometer and fire extinguishing means, and means responsive to a signal from said pyrometer that the temperature of the material on the extending part of said trough is at combustion level for initiating the operation of said extinguishing means.
